CLAIM

The ornamental design for an electrical connector housing, as shown and described.

DESCRIPTION

FIG. 1 is a top plan view of an electrical connector housing showing our new design;

FIG. 2 is a front elevational view thereof;

FIG. 3 is a bottom plan view thereof;

FIG. 4 is a rear elevational view thereof;

FIG. 5 is a right side elevational view thereof, the left side elevational view therof being a mirror image;

FIG. 6 is a cross-sectional view thereof, taken along 6—6 of FIG. 2; and,

FIG. 7 is a fragmentary rear and upper right perspective view thereof showing the area at the center of FIG. 5 on an enlarged scale.

FIG. 1

FIG. 3

FIG. 2

FIG. 4
